APPARATUS FOR WAX COATING SCIENTIFIC GLASSWARE

Walter E. Kirjian, Vineland, N. J., assignor to Owens-Illinois Glass Company, a corporation of Ohio

Application October 4, 1954, Serial No. 460,048

2 Claims. (Cl. 118—406)

The present invention is an improved method and apparatus for wax coating scientific glassware such, for example as pipettes, burettes, flasks, and the like.

Permanent graduations ordinarily including lines and numbers are applied to scientific glassware by a procedure generally involving wax coating and the entire exterior surface, placing the ware in a suitable numbering and lining machine which cuts through the wax coating and exposes the glass surface in the areas to be lined and numbered and then dipping such articles after the wax has set, into a bath of hydrofluoric acid which etches the exposed glass surfaces and permanently forms the lines and numbers, thereby providing the desired graduations.

Incident to performance of the lining and numbering step, the articles are supported at their ends in holders or chucks which frequently score or chip the wax coating and expose glass surfaces which should not directly contact the hydrofluoric acid, for the obvious reason that such would result in undesired etching of the end portions of the articles. In the case of pipettes or similar open-ended cylindrical articles, it is also necessary to seal the ends against entrance of the hydrofluoric acid to the interior, since otherwise undesired etching of the interior surfaces would also occur.

In consequence of the above it has been the practice, following the step of lining and numbering the wax coated tubes, to retouch the ends manually and by a separate operation, seal such ends and anchor them in a so-called "nail board" which serves as a support for a plurality of tubes while the free ends thereof are dipped into a liquid wax bath and later during immersion of the tubes in the etching bath of hydrofluoric acid.

An object of my invention is the provision of a novel method and apparatus for materially facilitating the so-called retouching operation and mechanizing the same, whereby the operator's efficiency and productive capacity may be very materially increased and a substantial saving in production costs effected.

It is also an object to provide a novel apparatus in which the conventional "nail board" support for the tubes, after having tubes loosely positioned thereon, is dipped into a bath of liquid wax to coat, seal, and anchor one end of the tubes in the nail board and then after the wax has set, inverting such board and mechanically lowering same to immerse the other end of the tubes in the wax bath to effect both sealing of the open end and coating of any scored portions.

Other objects will be in part apparent and in part pointed out hereinafter.

In the drawings:

Fig. 1 is a fragmentary sectional elevational view showing a nail board with pipettes positioned thereupon preparatory to immersion of the board into a body of liquid wax for the purpose of coating and sealing the lower ends and anchoring same in the nail board;

Fig. 2 is a view similar to Fig. 1 but showing the nail board inverted after anchoring the pipettes therein, the

2

free ends of the pipettes being projected into the wax to effect sealing and coating thereof;

Fig. 3 is an isometric view of one of the pipette supporting nail boards;

5 Fig. 4 is a detail section elevational view showing the manner in which the pipettes or other cylindrical articles are anchored in the nail board and their lower ends sealed against entry of the etching fluid;

10 Fig. 5 is a view more or less diagrammatically illustrating the mechanism whereby raising and lowering of the leveling tray on which the nail boards are supported may be effected; and

15 Fig. 6 is a fragmentary sectional view of one end of a pipette showing the wax coating thereon.

15 In the illustrated form of the apparatus involved, it comprises a tank 10 containing a body 11 of liquid wax whose upper surface is exposed; an invertible nail board 12 for supporting tubular glass articles 13; and a vertically movable leveling tray 14 intended to support the nail board 20 in either of the positions shown in Figs. 1 and 2, while the nail board and articles are moved relative to the bath of liquid wax.

25 As stated, heretofore, these pipettes or other tubular articles 13, prior to placement upon the nail boards will have been coated with wax but may have had some of the wax removed accidentally at the ends, incident to chucking in the lining and numbering machine and/or general handling. This coating 15 is shown upon the article 13 in Fig. 4.

30 The nail board 12 which supports the articles 13 throughout the retouching operation and later during immersion of the articles in the etching bath of hydrofluoric acid, may comprise a rectangular member provided on one surface with a plurality of recesses 16 and axially 35 positioned spikes or nails 17 which are driven through the board from the surface opposite that in which the recesses are provided. These spikes or nails are intended to enter one end of the tubular articles 13 and support the latter more or less loosely until the space between the periphery of the article and the side wall of the recess has been filled with wax 18 (as shown in Fig. 4). This wax 40 filler 18 performs the two-fold function of anchoring the article 13 in the recess and sealing off the opening to the interior at this end so as to prevent entry of the etching acid to the interior of the article. It is understood of course that the diameter of each of the recesses 16 is slightly greater than that of the article to be supported thereon so as to provide adequate space to accommodate sufficient wax to function as above explained.

45 After one of these leveling trays has been filled with the tubular articles, pipettes, for example, it is placed in the leveling tray 14 as shown in Fig. 1, preparatory to being lowered into the wax bath 11.

50 This leveling tray 14 is an open rectangular metal frame suspended from a guide rod 19 which extends vertically upward through a pair of stationary guides 20 and at its upper end is connected to a cable 21 running over a pair of pulleys 22 and thence downwardly for connection to a counterweight 23. The leveling tray is provided at 55 its lower end with a support 24 upon which the nail board may rest with the pipettes projecting upwardly therefrom. While in this position, the leveling tray is manually lowered sufficiently to completely submerge the nail board 12

60 in the bath of wax 11 and permit the wax to flow into the spaces about the lower ends of the pipettes and thereby fill the latter and anchor the articles to the nail board. Spaced above the support 24 is a pair of horizontally 65 spaced angle iron rails 25 which are intended to support the filled nail board when the latter is in an inverted position, as shown in Fig. 2. It is understood that prior to the positioning of the nail board and pipettes (as shown in

70

Fig. 2) the wax fillers 18 have set sufficiently to prevent premature displacement of the pipettes. The next step very obviously is to lower the leveling tray as illustrated in Fig. 2, so that the tip ends of the pipettes project into the liquid wax bath. At the proper time the leveling tray is elevated and during such movement, the excess wax flows by gravity from the tip ends of the pipettes and that remaining on the pipettes recoats the lower end and simultaneously seals the opening. Cooling air directed against the tubes by means of a fan (not shown) may be utilized to accelerate setting of the wax. Following this operation the nail board with the pipettes thereon is removed from the leveling tray and transported to another location where at the convenience of the operator the pipettes, still supported by the nail board is immersed in the hydrofluoric acid bath for the purpose of etching the exposed surfaces of the glass articles. After such etching has been completed, the wax is removed in any preferred or conventional manner, leaving the exterior surface with only the clearly etched lines and numerals thereon.

Modifications may be resorted to within the spirit and scope of the appended claims.

I claim:

1. In combination, a container for a bath of molten wax providing an exposed upper surface of such bath, a leveling tray positioned over said container and mounted for movement vertically relative to the latter, a carrier for wax coated glass tubes whose ends are to be dipped into the wax for additional coating and sealing, said carrier comprising a board provided on one side with a plurality of recesses and spikes individual to the recesses projecting axially outward from the latter, said spikes adapted to enter one end of such tubes and the tubes being loosely received in said recesses, a pair of vertically spaced supports on the leveling tray, said carrier adapted to be positioned upon the lower support with the tubes projecting upwardly during downward movement of the leveling tray into the bath of wax whereby the latter may

flow by gravity into the recesses to coat, seal, and anchor the lower ends of the tubes in said recesses, and the upper support being adapted to receive the carrier with the tubes suspended therefrom preparatory to dipping the free ends of such tubes into the molten wax bath.

2. In combination, a container for a bath of molten wax providing an exposed upper surface of such bath, a leveling tray positioned over said container and mounted for movement vertically relative to the latter, a carrier for wax-coated glass tubes whose ends are to be dipped into the wax for additional coating and sealing, said carrier comprising a board provided on one side with a plurality of recesses and spikes individual to the recesses projecting axially outward from the latter, said spikes adapted to enter one end of such tubes and the tubes being loosely received in said recesses, and means forming a part of the leveling tray for supporting the carrier in either of two positions in one of which the tubes project upwardly during downward movement of the leveling tray into the bath of wax whereby the latter may flow by gravity into the recesses to coat, seal, and anchor the lower ends of the tubes in said recesses while in the other position the tubes are suspended from said carrier preparatory to having their free lower ends dipped into the molten wax bath.
